UNITED STATES PATENT OFFICE.

ALBERT A. BRUDER, OF HOLLY, MICHIGAN.

FURNACE GRATE.

Application filed May 19, 1923. Serial No. 640,077.

To all whom it may concern:

Be it known that I, ALBERT A. BRUDER, a citizen of the United States of America, residing at Holly, in the county of Oakland 5 and State of Michigan, have invented certain new and useful Improvements in Furnace Grates, of which the following is a specification, reference being had therein to the accompanying drawings.

This invention relates to furnace grates, and has special reference to that class of grates which are detachable for repair or cleaning purposes, rockable for shaking down a fire, and composed of a plurality of units either of which may be rocked independent of the other units. Such a grate can be advantageously used in connection with furnaces, cooking ranges and structures having large combustion chambers or fire 15 boxes in which a large bed of burning fuel may be maintained.

One of the objects of my invention is to provide a grate of the above type that may be bodily shifted into an ash pit or chamber and quickly mounted to form the bottom of a combustion chamber or fire box, the grate being laid down or completely removed should it be necessary to repair or clean adjacent parts of the furnace structure.

Another object of this invention is to provide a grate composed of a plurality of rockable units, some of which are intermeshing and constructed to readily dispose of clinkers and other non-fusible material that may accumulate on the grate. All of the rockable units have a configuration to permit of ashes being easily disposed of without any danger of clinkers or even fuel material interfering with a rocking movement of the grate units.

A further object of this invention is to provide a grate composed of rockable units and novel means for rocking the units in synchronism, which means also permits of either grate unit being rocked while the others are held stationary.

The above and other objects are attained by a construction that will be hereinafter described and then claimed, and reference will now be had to the drawings, wherein—

Figure 1 is a longitudinal sectional view of a furnace grate in accordance with my invention, showing the grate in connection with a portion of a furnace;

Fig. 2 is a front elevation of the same, partly broken away and partly in section;

Fig. 3 is a perspective view of a portion

of an operating lever by which the grate units may be actuated;

Fig. 4 is a perspective view of a portion of the grate rocking mechanism showing 60 selective individual rockers;

Fig. 5 is a cross sectional view of the grate;

Fig. 6 is a horizontal sectional view of a portion of the furnace showing the grate in 65 plan;

Fig. 7 is an elevation of the inner side of a retaining member as mounted on a furnace wheel, and

Fig. 8 is a perspective view of a portion 70 of the same.

As showing the grate and its operating mechanism in connection with a furnace, I have illustrated the lower portion of the furnace including an ash pit formed by side 75 walls 1, a rear wall 2, a furnace front wall 3 and a top wall 4, said top wall supporting the walls 5 of a fire box or combustion chamber 6 which communicates with the ash pit 1 through an opening 7 in the top wall 4. 80 The rear wall 2 of the ash pit may have a flue opening 8 and the furnace wall 3 has an opening 9 the full width and depth of the ash pit so that ashes may be readily removed therefrom. The opening 9 is adapted to be 85 closed by a conventional form of door or doors (not shown).

The side walls 1 of the ash pit are provided with opposed inclined guideways 10 extending inwardly from the opening 9 to 90 the rear wall 2 and the inner ends of said guideways are in proximity to the top wall 4 so as to guide the rear rail 11 of a rectangular grate frame 12 into position to be raised to a horizontal position below the 95 opening 7. The front rail 13 of the grate frame 12 has angular lugs 14 adapted to engage pivoted hangers 15 suspended from the top wall 4 at the sides of the ash pit. When the forward rail 13 of the grate frame is raised the lugs 14 ride into engagement with the hangers 15, cause the same to momentarily swing forward, and then said hangers engage under the lugs and cooperate with the inclined guideways 10 in supporting the 100 grate frame 12 in a horizontal position in the upper part of the ash pit. The opening 9 permits of the grate frame being placed on the guideways 10, pushed inwardly into the 105 upper part of the ash pit, and then raised and automatically fastened in position.

Should it be necessary to clean the grate, the

lower part of the fire box, or remove the grate for any purpose, the hangers 15 can be swung forwardly to release the forward edge of the grate frame, permit it to be 5 solely supported by the guideways 10, and then shifted forwardly out of the ash pit.

The rails 11 and 13 of the grate frame 12 are provided with sets of longitudinally alining sockets 16 for grate rocker shafts 17, 18, 19 and 20, the shafts 17 and 18 being disposed in parallelism at one side of the central longitudinal plane of the ash pit and the shafts 19 and 20 disposed in parallelism at the opposite side of such vertical plane. The shafts 17 and 20 are provided with grate units 21 having straight edges adjacent the side rails of the grate frame 12, as best shown in Fig. 6, and the shafts 18 and 19 have intermeshing grate 10 units 22 which cooperate with the grate units 21 in providing a grate of large area. The straight edges of the grate units 21 are curved upwardly, as best shown in Fig. 5 so as to preclude ashes or burning coals 15 from falling over the edges of said units and becoming wedged between said units and the grate frame 12. All of the grate units are adapted to be swung downwardly, the units 21 swinging away from the side 20 rails of the grate frame 12 and the units 22 swinging away from each other. To permit of the units 21 being easily swung into the frame 12, the straight edges of said units have depending flanges 23 and the confronting edges of the units 22 are provided with 25 similar flanges or shoes 24. These flanges or shoes will crush any clinkers or coals partially burned that may lodge between the edges of the units 22 or between the 30 units 23 and the frame 12.

The outer ends of the shafts 17 to 20 inclusive extend through openings 25 provided therefor in the upper edge or wall of the doorway 9 and supporting these shafts 45 in an operative position so that the same may be rocked is a retaining member 26 adapted to have its ends 27 supported on pins or bosses 28 of a wall 3, said pins or bosses having pivoted latches 29 that may 50 be swung on to keepers 30 of the retaining member 26. The keepers 30 support the latches in horizontal positions holding the retaining member 26 against the inner face 55 of the wall 3, and with the retaining member insertible through the doorway 9 it can be easily raised and set on the pins or studs 28 after which the latches 29 may be swung into position. The upper edge of the retaining member 26 is cut away and formed 60 with sockets 31 to cooperate with the wall 3 and the socket 16 of the grate frame 12 in supporting the shafts 17 to 20 inclusive so that the same may be rocked.

On the outer ends of the shafts 17 to 20 65 inclusive are upstanding cranks 32 and piv-

otally connected to the ends of said cranks are angular rocker members 33 the long arms of which serve as handles and the short arms as projections 34 to engage in notches 35 of a reciprocable rocker bar 36 slidable in a 70 guide 37 carried by the furnace wall 3. One end of the rocker bar 36 is pivotally connected, as at 38 to an operating lever 39 pivotally attached to the furnace wall 3. The upper end of the operating lever 39 has a 75 handle 40 terminating in an offset projection 41 adapted to be engaged by a keeper 42 pivotally attached, as at 43 to the furnace wall 3. The keeper has curved side lips 44 adapted to be engaged by the projection 41 so that said projection may easily ride 80 into and out of engagement with the keeper 42. The keeper 42 may be held in a raised position while the operating lever 39 is manually oscillated. With the keeper 42 in 85 engagement with the projection 41 the grate shaking mechanism is in a locked condition and the grate units held to maintain a fire bed within the fire box or combustion chamber 6.

Below the reciprocatory bar 36, at each set of cranks 32, is a slotted ledge 45 and the projections 34 of the individual rocker members 33 must aline with the slots in the ledges 45 before the projections 34 can be 90 swung out of engagement with the bar 36. When the handle portion of any rocker member is raised the shaft from which said rocker member is supported may be rocked or oscillated independent of the other shafts which are held by virtue of the bar 36 and the operating lever 39. It is through the medium of the individual rocking members that grate units may be selected for individual dumping of clinkers or other waste material on the grate. When all of the rocker shafts are coupled to the bar 36 the operating lever 39 may be oscillated to vibrate the grate units and shake down a fire bed on the grate. It is only when some particular portion of the fire bed requires agitation that either of the individual rocker members is used, otherwise the rocker members are actuated in synchronism from the 100 lever 39. Since the individual rocker members are not directly connected to the bar 36 it is obvious that the grate may be bodily dropped and removed from the ash pit without interfering with the operating mechanism as carried by the furnace wall 3. Then again, the crank ends of said rocker shafts facilitate manipulation of the grate 105 as a whole.

While in the drawings, there is illustrated a preferred embodiment of my invention, it is to be understood that the structural elements are susceptible to such variations and modifications as fall within the scope of the appended claims.

What I claim is:—

1. The combination with a fire box and ash pit, of guideways in the ash pit, a grate frame slideable on said guideways and adapted to be fixed relative to the fire box, and rockable units carried by said grate frame and operable at the front of said ash pit to shake down a fire in the fire box on said grate units. 5
2. The combination called for in claim 1, and means in front of said ash pit adapted for rocking said grate units in synchronism and adapted to permit of individual rocking of either grate unit. 10
3. A furnace grate comprising a frame, rock shafts supported by said frame, grate units carried by said rock shafts in said frame, individual depending rocker members pivotally supported from the outer ends of said rock shafts, and reciprocatory means above said rock shafts engaged by said individual rocker members so that all of said members may be actuated in synchronism, said pivoted rocker members being arranged to have the outer ends thereof raised to disengage said rocker members from said actuating means. 20
4. A furnace grate as called for in claim 3, wherein said rock shafts have upwardly extending cranks supporting said pivoted rocker members. 30
5. A furnace grate as called for in claim 3, wherein said rock shafts are disposed in sets with some of said grate units provided with intermeshing crushing shoes adapted to crush clinkers or coals that may lodge between adjacent edges of said units. 35
6. The combination with an ash pit hav-
- ing a doorway, of guideways in the ash pit, a grate frame having one end thereof normally supported by said guideways, 40 hangers supporting the opposite end of said grate frame, rock shafts carried by said grate frame and extending through the upper edge of the doorway of said ash pit, a retaining member supporting said rock shafts 45 in the upper edge of the doorway of said ash pit, grate units carried by said rock shafts in said grate frame, and means at the outer ends of said rock shafts to facilitate rocking said shafts in synchronism. 50
7. The combination called for in claim 6, wherein said means includes individual rocker members to permit of either shaft being rocked independent of the other shafts. 55
8. A furnace grate comprising a frame, sets of rock shafts supported by said frame, grate units carried by some of said shafts and having intermeshing edges adapted to be swung downwardly away from each other, and grate units carried by the other of said shafts adapted to be swung downwardly towards each other. 60
9. A furnace grate as called for in claim 8, and means articulated with said shafts 65 for either actuating said shafts in synchronism or to permit of either shaft being actuated independent of the other shafts.

In testimony whereof I affix my signature in presence of two witnesses.

ALBERT A. BRUDER.
